ELECTRICAL SIGNAL REPEATING SYSTEM

Edward E. Kleinschmidt, Highland Park, and
David S. Hulfish, Chicago, Ill., assignors to
Teletype Corporation, Chicago, Ill., a corpora-
tion of Delaware

Original application December 13, 1929, Serial No.
413,838, now Patent No. 2,153,574, dated April
11, 1939. Divided and this application May 20,
1938, Serial No. 208,990

18 Claims. (Cl. 178—2)

This invention relates to automatic switching
systems and apparatus for signaling systems.
More particularly, the invention relates to auto-
matic switching systems and apparatus for an
exchange system adaptable for combined service,
alternatively telegraphic or telephonic communica-
5 tion.

Telegraph signals are characterized by direct
10 currents interrupted in code manner to form
spacing and marking signal impulses, while tele-
phone signals are characterized by a variable cur-
rent varying in voice frequencies. Specially de-
signed equipment is required for permitting both
15 telegraph and telephone communication over a
single circuit and through conventional auto-
matic telephone switching circuits and appa-
ratus.

Automatic telephone switching systems are
20 operated by dialed signal impulses of direct cur-
rent to which the switching equipment responds
to effect connection with a called line. Main-
tenance of an established connection is ordi-
narily controlled by preserving a direct or holding
25 current through the calling substation. Re-
lease of the equipment is accomplished by discon-
tinuance of the direct current for a predeter-
mined interval.

A complete system for rendering telegraph and
20 telephone service alternatively from an integral
switching equipment in which switches are com-
mon to both services is disclosed and claimed in
a copending application Serial No. 413,838 filed
December 13, 1929, patented April 11, 1939, No.
2,153,574, by E. E. Kleinschmidt and D. S. Hul-
35 fish of which application the present applica-
tion is a division, specifically with reference to
the telegraph repeating circuits and devices dis-
closed in the original application.

In general, the present invention contemplates
40 a directory number or combination of signal
codes identifying severally each telegraph set
in a combined telegraph and telephone exchange
system having automatic apparatus such that,
when such a telegraph directory number is
45 dialed, the automatic equipment will operate to
set up a communicative connection including
telegraph translating and repeating equipment.
After the connection has been completed through
to the called substation, apparatus at the call-
50 ing end of the connection will translate direct
current signals originated at the calling sub-
station into alternating currents substantially of
voice frequency, and apparatus at the called end
of the connection will retranslate the alternat-
55 ing currents into direct current signal impulses

for operating the telegraph receiving apparatus.
Provision is made for permitting telegraph sig-
naling in both directions following establish-
ment of a connection, and for restoration of the switch-
ing equipment at the end of communication.

The main object of the present invention is
the provision of a single repeating device which
is capable of effecting the functions incident to
maintaining an established connection and to
telegraphing between the connected stations.

It is a feature of the complete system of the
invention of the parent application that a connec-
tion may be established from a substation of
one central office to a trunk line extending to
another central office, and thence extended to a
15 substation of the second mentioned central office,
automatic switches being operated in both cen-
tral offices under control of the first mentioned
substation.

It is a feature of the invention of the parent
application that automatic switches shall be op-
erated to establish a telegraph connection ex-
actly as they are operated to establish a tele-
phone connection; namely, by impulses of direct
25 current. It follows that when establishing a
connection for telegraph communication, it is
required to repeat signals of direct current over
the trunk circuit to control selective adjustment,
then to maintain an effected adjustment, and to
control subsequent disconnection of switches,
30 and concurrently, while communicating tele-
graphically, it is required to repeat telegraph
signals comprising currents of voice frequency
over the trunk circuit.

A connection may be established for telephone
35 communication or a different connection may
be established for telegraph communication using
the same subscriber lines and some of the same
central office equipment.

A better understanding of the invention may
40 be had from the following description, taken in
conjunction with disclosures of the parent appli-
cation and with the accompanying drawing
wherein:

Fig. 1 is a diagrammatic showing of unoper-
ated switches and circuits for forming a pro-
posed communication circuit from a calling to a
called substation shown before switching con-
nections have been made;

Fig. 2 is a circuit diagram showing the com-
pleted circuit connections with a marking sig-
nal condition between a calling substation and a
called substation for telegraph communication;

Fig. 3 is a circuit diagram of a selector; and

Fig. 4 illustrates a modified circuit embodying

the principles of the repeater system of the invention.

Referring to Figs. 1 and 2, two substations 1 and 2, remote from each other, are shown, each station being provided with a telegraph set and optionally with a telephone set also. Extending from each of the substations are their individual signaling lines 3, 4 and 5, 6, respectively, over which telegraph communication may be carried 10 on subsequent to the dialing of a telegraph directory number.

The signaling line 3, 4 extends to the rotary line switch 7, which is of well-known construction and which, in response to closure of the circuit loop at the substation, operates automatically to find an idle selector 8, the controlling circuits of which are connected over conductor 9 to a bank contact in rotary switch 7.

After seizure of switch 8 by operation of non-numerical switch 7, an operator at station 1 may dial 768,644 to control switches 8, 12, 28, 37, 39 to establish a telephone connection with station 2, or may dial 8,768,855 to control switches 8, 16, 12, 28, 37, 53 to establish a telegraph connection 25 with station 2.

Selector 8, which also is of well-known construction, operates in response to the first dialing signal or digit signal "8" from substation 1, to adjust the wipers of the switch 8 vertically to a selected position with reference to its bank contacts, as illustrated by upper dotted line, after which the wipers of the switch 8 rotate to engage an idle junction circuit 13 extending to a repeater relay set 14, which is arranged to receive impulses of direct current from substation 1 and to retransmit signals of direct current for switch control as well as signals of voice frequency for telegraph transmission purposes.

Upon seizure of the repeater set 14 by switch 8, the substation 1 is connected conductively to the repeating relay 23, which becomes energized, and its armature 24, through inductance 25, controls a rotary switch 15 of construction similar to the line switch 7, which operates to connect with an idle selector 16. Relay 23 remains energized over a circuit closed through a dialing transmitter at substation 1.

Upon dialing of a second directory digit, each break of the dial at substation 1 releases the armature of the repeating relay 23, which interrupts direct current from switch 16 flowing through armature 24 and inductance 25, and substitutes an alternating current of voice frequency originated in induction coil 31. There is in the circuit of this alternating current at this time, no apparatus responsive thereto, and accordingly, the alternating current is without effect. However, each break of the contact of armature 24 operates the switch 16 selectively and positions its wipers, as indicated by dotted line, to select an idle selector 12. Similarly, the dial signal impulses of the third directory digit at substation 1 are repeated by repeater 14 to the selector switch 12, and an idle junction circuit is selected which will extend the circuit of armature 24 to an idle selector 28. Fourth dialing impulses are effective to operate the selector switch 28, fifth dialing impulses for "8" are effective to operate a selector switch 31, and sixth and seventh dialing impulses 70 are effective to operate a final connector switch 53 containing as a part thereof the repeater equipment 42. In progress of switching operations subsequent to the operation of switch 8, armature 24 of relay 23, in response to closed-circuit controlling condition at substation 1, has

closed a circuit for direct current through inductance 25, and in response to open-circuit controlling condition at substation 1, has closed the circuit through inductance coil 31 to supply current of voice frequency which has been futile because the circuits to which the voice frequency currents have been applied have not included any device responsive to currents of voice frequency. 5

Upon connecting with the called line, relay 342 is energized, as shown in Fig. 3, to close its contacts in the circuit of secondary winding of induction coil 46, and repeating relay 48 is energized to control the energizing circuit of relay 45, which is responsive to currents of voice frequency, thus completing the circuits of the telephone repeating system. 10 15

Referring more particularly to Fig. 2, the circuits of the repeating system may be traced in three line sections. First or originating line section extends from grounded battery, through a 20 winding of relay 23, a conductor 13, switches 8 and 7, conductor 4, key 74, permutation transmitter 87, recorder magnet 86, returning over key 74, conductor 3, switches 7 and 8, a conductor 13, and a winding of relay 23 to ground. Second or terminating line section extends from grounded battery, through a winding of relay 48, contacts of switch 53, line conductor 5, contacts of relay 376, winding of relay 393, recorder magnet 394, and permutation transmitter 395, returning over contacts of switch 376, line conductor 6, contacts of switch 53, and a winding of relay 48 to ground. 25 30

Third or intermediate line section extends, for transmitting from substation 1, from secondary 35 winding of induction coil 31, whose primary winding is indicated as a source of alternating current of voice frequency, through condenser and back contact of armature 24 when repeating relay 23 is deenergized, through contacts of 40 switches 15, 16, 12, 28, and 37, armature 47 and front contact, condenser 44 and signal-receiving relay 45 responsive to currents of voice frequency, returning to induction coil 31 over parallel wiring in the several switches. A marking signal in the 45 repeating system is constituted by a condition of current in the first and third line sections, energizing both relays 23 and 48 and holding open the back contacts of both armatures 24 and 47, thus holding open the circuits of both induction coils 50 31 and 46 with no voice frequency current in the intermediate line section, but with a closed circuit carrying direct current in the intermediate line section from grounded battery, through a winding of relay 43, contacts of automatic 55 switches 37, 28, 12, 16, 15, contact of energized relay 23, and inductance 25, returning through contacts of the automatic switches and a winding of relay 43 to ground. 60

Functions of repeater 14 in the process of establishing a telegraph communicative connection are solely to retransmit signals which are of direct current nature, but when the connection has been established and the alternating current voice frequency relay 45 has been included in the 65 communicative connection, the functions of the repeater 14 are increased to the double requirement, first, receiving direct current signal spacing impulses of telegraph communication nature and retransmitting each such received impulse of 70 spacing nature in the form of a time period of alternating current voice frequency effective upon alternating current frequency relay 45, and second, receiving direct current signal marking impulses of switch-controlling nature and retrans- 75

mitting each such received impulse in the form of a repeated direct current impulse effective upon the relay 43 to energize the relay 43 for purposes of holding the final connector switch and other switches of the connection in communicative condition.

- The method of operating relay 43 to effect maintenance of an established connection comprises the steps of energizing relay 43 in response to a closed circuit condition corresponding to a telegraph marking signal at the calling substation, deenergizing relay 43 in response to an open-circuit condition corresponding to a telegraph spacing signal at the calling substation 1, maintaining a maximum length of spacing signal during telegraph communication below a predetermined time value, and effecting discontinuance of the said established connection in response to a spacing signal at substation 1 which exceeds the said predetermined time period. Apparatus to this end is illustrated in Fig. 3 which shows pertinent elements copied from Fig. 6 of the parent application.

Referring to Fig. 2, relay 411 being inactive, the relay 23 responds to signaling conditions in permutation transmitter 87 at substation 1, and relay 43 is wholly controlled by armature and front contact of relay 23, being therefore indirectly controlled by the transmitter 87. The aforesaid time period is determined by adjustment of the time element in slow-to-release relay 326, Fig. 3.

Discontinuance of the established connection is effected by deenergization of relay 362 permitting armatures 373 and 386 to disconnect the line conductors 5, 6 from the winding of relay 48. Deenergization of relay 362 is effected in response to a spacing impulse generated at substation 1 and having a time value greater than the aforesaid time period. At substation 1, Fig. 2, switch 74 is reversed by manual control, thus opening the energizing circuit of relay 23. Deenergization of relay 23 by its front contact opens the energizing circuit of relay 43. Deenergization of relay 43, Fig. 3, opens the energizing circuit of slow-to-release relay 326, which is the starting condition for the predetermined time period. At expiration of the predetermined time period, relay 326 releases its armature 328, which interrupts the holding circuit for relay 362. Armatures 373 and 386 are released and opening of their contacts interrupts the connection of line conductors 5 and 6.

Throughout the duration of telegraph communication in an established connection, armature 24 and front contact in relay 23 are utilized continuously in vibratory manner to control circuits and apparatus local to the central office to maintain the switches of the connection in their adjusted position. To effect transmission of significant telegraph signals by use of the same repeating relay 23, a back contact is provided for armature 24 and a telegraph communication circuit is provided including secondary winding of an induction coil 31 as a source of alternating-current voice-frequency energy, a condenser 19, back contact and armature 24, adjusted brushes and contacts in switches 15, 16, 12, 28, 31, armature 41 and front contact of energized relay 48, condenser 44, winding of alternating-current relay 45, returning through companion contacts and brushes in the said automatic switches to the secondary winding of induction coil 31. Current in this circuit constitutes a telegraph signal of spacing nature.

Alternating current from induction coil 31 is received as a signal of spacing nature by relay 45 which operates the armature 51 to connect together the line conductors 5, 6 through branching local conductors 98 and 99, thus shunting the substation receiving magnet 394 which, by deenergization, manifests the signal of spacing nature generated by transmitter 87 and repeated first by relay 23 and again by relay 45.

Reflection estoppel is effected by a circuit including battery, upper winding of relay 48, local conductor 98, contact and armature 51 of energized relay 45, local conductor 99 and lower winding of relay 48 to ground return, holding energized the repeating relay 48 throughout the duration of a spacing signal originated by transmitter 87.

Fig. 4 illustrates a telegraph repeater system embodying the invention in simplified form.

A first line section includes battery 100, winding of repeating relay 101, line conductor 102, winding of substation relay 103, contacts of transmitting key 104 and ground return, with a shunting path through local conductor 105 and open armature 106 of relay 107 and contact to ground, forming a closed telegraph circuit energized by battery 100 and controlled either by key 104 to open the circuit to deprive both relays 101 and 103 of energy, or by armature 106 and contact to form a shunt around the winding of relay 103, depriving relay 103 of current but maintaining current in the winding of repeater relay 101.

A second and similar line section includes battery 120, relay 121, line conductor 122, relay 123, key 124, local conductor 125, armature 126, and relay 127.

A third line section 108 is without current or in open-circuit condition representing a marking telegraph signal condition. A circuit through conductor 108 may be closed by armature 109 when released, including battery 110, back contact and armature 109, conductor 108, armature 129 and front contact, winding of relay 127 and ground return, or, alternatively, by armature 129 when released, including battery 130, back contact and armature 129, conductor 108, armature 109 and front contact, winding of relay 107 and ground return.

Two methods of working telegraph circuits; namely, the open and closed circuit methods, are well known. The open circuit method is almost exclusively employed in England, whereas the closed circuit method is in most extensive use in the United States. A circuit worked upon the open method is one in which no current traverses the circuit when idle, and, as a corollary, batteries are required at both ends of the circuit. For further details on these methods, reference should be made to "Telegraphy," Herbert, London, Whittaker & Company, 1906. The term "open circuit" used in the claims hereof is to be in accordance with the foregoing definition.

In operation, a signal of marking nature is constituted by the condition shown in Fig. 4 with relays 103, 123 energized at terminal stations and with relays 101, 121 energized at a repeating station. A signal of spacing nature is propagated by opening key 104, deenergizing the home relay 103, and the repeating relay 101, releasing the armature 109 which closes a circuit over conductor 108 to energize the relay 127 and to attract armature 126 which shunts the winding of relay 123, deenergizes relay 123 and reproduces in relay 123 the signal condition initiated by key 104. Reflection estoppel is effected

by a circuit including battery 120, winding of relay 121, armature 126 and contact and ground return which holds repeating relay 121 energized throughout the duration of spacing signal originated by key 104.

Two species of embodiments of the invention have been illustrated herein, and it is obvious that further species will result in applying the invention to variant systems of telegraph apparatus by one skilled in the art to which the invention pertains.

What is claimed is:

1. The method of transmitting telegraph intelligence from a point of origin to a remote point which comprises the steps of establishing a communicative telegraph connection between said two points under control of the point of origin, and thereafter transmitting in alternation under control of said point of origin currents for maintaining said established connection and currents constituting transmission of intelligence.

2. The method of transmitting telegraph intelligence from a point of origin to a remote point which comprises the steps of establishing a communicative telegraph connection between said two points under control of the point of origin, thereafter transmitting in alternation under control of said point of origin currents for maintaining said established connection and currents constituting transmission of intelligence, and effecting discontinuance of said telegraph connection by discontinuing said maintaining currents.

3. The method of transmitting telegraph intelligence from a point of origin to a remote point through two intermediate points which comprises the steps of establishing a communicative telegraph connection from said point of origin through first and second intermediate points to said remote point, thereafter transmitting intelligence signals from said point of origin to said first intermediate point, repeating said intelligence signals and generating currents for maintaining said established connection, transmitting said repeated intelligence signals and said maintaining currents in alternation between said first intermediate point and said second intermediate point, repeating said intelligence signals at said second intermediate point, and retransmitting said last mentioned repeated signals to said remote point.

4. The method of transmitting telegraph intelligence between a point of origin and a remote point through two intermediate points which comprises the steps of establishing a communicative telegraph connection from said point of origin through first and second intermediate points to said remote point, thereafter maintaining said established connection under control from said point of origin while transmitting intelligence signals by direct current signals from said remote point to said second intermediate point, repeating said signals and retransmitting from said second to said first intermediate point, again repeating said signals, and retransmitting by direct current signals from said first intermediate point to said point of origin.

5. The method of transmitting telegraph intelligence between a point of origin and a remote point through two intermediate points which comprises the steps of establishing a communicative telegraph connection from said point of origin through first and second intermediate points to said remote point, thereafter maintaining said established connection by continuous

direct current between said first and second intermediate points under control from said point of origin while transmitting intelligence signals by direct current signals from said remote point to said second intermediate point, repeating said intelligence signals and converting into alternating currents and retransmitting from said second to said first intermediate point over the conductors carrying the connection-maintaining direct current, again repeating said intelligence signals and converting into direct current signals, and retransmitting by direct current signals from said first intermediate point to said point of origin.

6. In a telegraph repeating system, means for establishing a communicative telegraph connection between two stations, means for transmitting direct current signals in alternation with alternating current signals over a portion of said established connection, means responsive to said direct current signals and effective to maintain said connection, and repeating means responsive to said alternating current signals and effective to convert said alternating current signals into direct current signals and to retransmit the direct current signals.

7. In a telegraph repeating system, means for establishing a communicative telegraph connection from a first station through first and second intermediate switching points to a second station, means to transmit direct current signals from said first station to said first switching point, means to repeat said signals and to convert said signals into alternating current signals, means to transmit said alternating current signals from said first to said second switching point, and means to repeat said signals and to convert said alternating current signals into direct current signals and to transmit said direct current signals from said second switching point to said second station.

8. In a telegraph repeating system, means for establishing a communicative telegraph connection from a first station through first and second intermediate switching points to a second station, means to transmit direct current signals from said first station to said first switching point, means to repeat said signals and to convert said signals into alternating current signals, means to transmit said alternating current signals from said first to said second switching point, means to repeat said signals and to convert said alternating current signals into direct current signals and to transmit said direct current signals from said second switching point to said second station, and means at said first switching point to generate connection-maintaining signals and to transmit said maintaining signals alternately with said alternating current signals.

9. In a telegraph repeater system, a repeating relay responsive to direct current code signals and having front and back contacts, a circuit including a source of direct current, one of said contacts and a relay responsive to direct current, and a further circuit including a source of alternating current, the other of said contacts and a further repeating relay responsive to alternating current.

10. In a telegraph repeater system, line-switching means, a repeating relay responsive to direct current code signals and having front and back repeating contacts, a circuit including a source of direct current, one of said contacts and a relay responsive to direct current and effective to con-

- trol said line-switching means, and a further circuit including a source of alternating current, the other of said contacts and a further repeating relay responsive to alternating current.
- 5 11. In combination, two stations, a central office through which said stations may be connected, switching mechanism including a telegraph repeater in the central office, means for connecting said stations through said central office, and additional means for connecting said stations, said additional means including said switching mechanism with the telegraph repeater.
- 10 12. In combination, two stations, a central office through which said stations may be connected, switching mechanism including a telegraph repeater in the central office, means for connecting said stations through said central office, additional means for connecting said stations, said additional means including said switching mechanism with said telegraph repeater, and means whereby the dialing of the directory number determines which of the two said means shall be included in the connection.
- 15 13. In combination, a first station, a second station, a first path between the two stations, a second path between the two stations, said second path including telegraph repeating mechanism, and means at each station for selecting either 20 one of the paths to the other station and establishing a connection therethrough.
- 20 14. In a telegraph repeater, a closed circuit line, an open circuit line, and means comprising 25
- a set of telegraph repeating relays associated with said lines and adapted to reproduce in each line the telegraph signals originating in the other line.
- 15 15. In a telegraph repeater system, two telegraph stations, two repeating stations, a closed circuit line connecting each of the telegraph stations with one of the repeating stations, and an open circuit telegraph line connecting the two repeater stations to each other.
- 10 16. In a telegraph repeating system, a plurality of closed circuit lines, an open circuit line, repeating relays controlled by said closed circuit lines to repeat signals into said open circuit line, and further repeating relays controlled by said 15 open circuit line to repeat signals into one of said closed circuit lines.
- 15 17. In a telegraph repeating system, a plurality of closed circuit lines, an open circuit line, repeating relays having windings connected to said 20 closed circuit lines and having contacts connected to said open circuit line, and further repeating relays having windings connected to said open circuit line and having contacts connected to said closed circuit lines.
- 25 18. In a telegraph repeater system, a first closed circuit line section, a second closed circuit line section, and means to repeat signals from one of said line sections into other of said line sections, said means comprising relays and an 30 open circuit section.

EDWARD E. KLEINSCHMIDT.
